PAUL A. MOESSMER, OF LOS ANGELES, CALIFORNIA

REFUSE-DISPOSAL APPARATUS

Application filed April 13, 1927. Serial No. 183,529.

My invention relates to disposal apparatus for domestic refuse, and it has for a purpose the provision of an apparatus which is associated with the drainboard of a sink and the wall of a house to permit the disposal of refuse through the drainboard and the ultimate removal of the refuse from the outside of the house, thereby eliminating the necessity of carrying the refuse out of the house.

It is also a purpose of my invention to provide a refuse disposal apparatus of the above described character which permits disposal of perishable refuse, such as garbage, separately from imperishable refuse, such as cans, bottles and the like, the garbage being deposited in one receptacle and the imperishable refuse in another, thereby permitting the separate collection of the two.

I will describe only one form of refuse disposal apparatus embodying my invention and will point out the novel features thereof in claims.

In the accompanying drawings,

Figure 1 is a view showing in perspective one form of refuse disposal apparatus embodying my invention in applied position to the outer wall of a house and the drainboard of a sink;

Figure 2 is a fragmentary perspective view of the outside of the house wall with the housing of the apparatus in applied position therein;

Figure 3 is a vertical sectional view of the apparatus taken on the line 3—3 of Figure 1;

Figure 4 is a vertical sectional view taken on the line 4—4 of Figure 3;

Figure 5 is a vertical sectional view taken at right angles to Figure 4, with the chute in the position it occupies when applying or removing the same to or from the upper housing;

Figure 6 is a reduced plan view of the annulus and finish plate of the receptacle;

Figure 7 is a fragmentary sectional view showing the positioning lug for the annulus;

Figure 8 is a fragmentary sectional view showing the chute lug.

Referring specifically to the drawings, my invention, in its present embodiment, comprises a housing H formed of sheet metal or

any other suitable material, and preferably of rectangular form, the housing in applied position being locked beneath the drainboard D of a sink S and extending through the outer wall of a house, as illustrated in Figure 55 2, so that its outer side is substantially flush with the outer surface of the wall. By means of a partition 15, the housing is divided interiorly into compartments 16 and 17, to which access may be had for inserting or removing cans or receptacles 18 and 19, respectively, through the medium of a door 20 hinged along its lower edge so that in opening it is swung downwardly. The top of the housing is provided with an elongated opening 21 conforming in contour to a housing extension H' likewise formed of sheet metal or other suitable material and supported on the top of the housing H in surrounding relation to the opening 21, as clearly illustrated 70 in Figure 3. The top of the housing extension is provided with an upstanding collar 22 which, as shown in Figure 7, is provided with a V-shaped notch 23 in which is adapted to be received a V-shaped lug 24 formed on 75 the outer periphery of an annulus 25, the latter being insertible into the collar, as illustrated in Figure 5.

This annulus 25 is formed integral with a finish plate 26 adapted to lie flush with the upper surface of the drainboard D when in applied position thereto, as illustrated in Figure 3, and provided on its under side with L-shaped tongues 27 which are adapted to engage within the tile work or other surface finish of the drainboard for securing the plate permanently within the drainboard.

The annulus is provided interiorly with an annular flange or collar 28 adapted to engage an annular flange 29 on the upper 80 end of a chute S in a manner to support the chute in depending relation to the annulus and so that such chute will extend downwardly through the collar 22 into the housing extension H'. The chute S is rotatable 95 in the annulus 25 to occupy either of two extreme positions defined by diametrically opposed lugs 30 in depending relation to the flange 28, as shown in Figures 3 and 6, and a third lug 31 on the outer surface of the 100

chute S. This latter lug 31 also engages the under side of the flange 28 to prevent accidental upward movement of the chute within the annulus and to thereby insure the easy 5 rotation of the chute to either of its extreme positions. In order to permit the insertion of the chute into the annulus, the flange 28 is recessed or slotted, as indicated at 32, in Figure 6, and through this slot the lug can 10 be extended to engage beneath the flange 28. When the lug is moved into registration with the slot it will be clear that the chute can be removed for cleaning.

The upper or entrance end of the chute S 15 is normally closed by a cover plate 33 which may be completely removable from the annulus 25 or hingedly connected thereto, as desired. The lower end of the chute is constructed to provide a laterally disposed opening 34 which is normally closed by a gate or door 35 of the same ovate contour as the opening and hingedly supported at its upper end, as indicated at 36, to swing upwardly, the gate being yieldably urged to closed position 20 by means of a spring 37 associated with the hinge 36. It will, of course, be understood that the spring is relatively weak, so as to permit the weight of refuse deposited into the chute to open the gate in allowing the 25 refuse to be discharged from the chute. This gate 35 may be removable or dispensed with but when in place functions to prevent up-drafts in the chute and the passage of odors upwardly of the chute.

35 In practice, the cans or receptacles 18 and 19 disposed within the compartments 16 and 17 of the housing H are designed to receive perishable and imperishable refuse, respectively, and when these cans are in applied 40 position, as shown in Figure 2, they are in refuse receiving relation with respect to any refuse discharged into the housing through the opening 21. When it is desired to discharge perishable refuse into the receptacle 18, the cover 33 is first removed and the chute S turned so that its discharge end is disposed directly above the receptacle 18. The refuse may be now deposited into the chute and through the medium of the latter discharged into the receptacle, the gate 35 opening under the weight of the refuse, as has been described. When discharging imperishable refuse into the receptacle 19, the chute S is turned to its other extreme position, as 45 indicated in dash lines in Figure 4, in which the discharge end is disposed directly above the receptacle 19. It will be understood that by depositing the refuse into the chute it will be delivered to the receptacle. The movement of the chute S to either of its two extreme 50 positions, as well as its removal from the annulus, is facilitated by the provision of a lip 38 formed interiorly of the chute at its upper end.

60 65 Incident to the collection of the refuse

by public carriers, the cans 18 and 19 can be removed from the housing H and emptied at a point exteriorly of the house, access being gained to the housing by opening of the door 20.

70 Although I have herein shown and described only one form of refuse disposal apparatus embodying my invention, it is to be understood that various changes and modifications may be made therein without departing from the spirit of the invention and the 75 spirit and scope of the appended claims.

I claim as my invention:

1. A refuse disposal apparatus comprising 80 a chute mounted with its entrance end in the drain-board of a sink, a housing below the chute in which may be placed a pair of receptacles to receive refuse discharged from the chute, means for mounting the chute in the drain-board of a sink for movement to occupy either of two extreme positions in one of which refuse will be discharged into one receptacle and in the other of which refuse will be discharged into the other receptacle, and means on the chute accessible through the upper end thereof by which the chute may be manually moved to either of said positions.

2. A refuse disposal apparatus comprising 85 a chute mounted with its entrance end in the drain board of a sink, a housing below the chute in which may be placed a pair of receptacles to receive refuse discharged from the chute, said chute being supported for movement to occupy either of two extreme 90 positions in one of which refuse will be discharged into one receptacle and in the other of which refuse will be discharged into the other receptacle, and a gate for closing the discharge end of the chute yieldably urged 95 to closed position.

3. In a refuse disposal apparatus, a chute having a lateral discharge opening, and means for mounting the chute in the drain-board of a sink to allow the chute to be 100 moved to either of two extreme positions in which the discharge opening occupies either of two extreme positions, said mounting comprising an annulus having an interior flange, a flange on the chute engaging the flange of the annulus to support the chute for rotation in the annulus, and co-acting lugs on the chute and annulus for limiting the 105 rotational movement of the chute in either direction to define the two extreme positions.

4. In a refuse disposal apparatus, a chute having a lateral discharge opening, means for mounting the chute in the drainboard of a sink to allow the chute to be moved to either of two extreme positions in which the discharge opening occupies either of two extreme 110 positions, and a closure for the lateral opening opening outwardly and yieldably urged to closed position.

5. A refuse disposal apparatus compris- 115

- ing a housing having an opening in the top thereof and an open side, a partition within the housing for dividing the latter into two compartments, a door for closing the open side of the housing, a housing extension on the top thereof in surrounding relation to said opening, a collar on the extension, an annulus removably fitted in the collar, a finish plate on the annulus, a chute rotatable in the collar and having a laterally disposed discharge end, said chute being rotatable in the annulus to occupy either of two extreme positions in which its discharge end is disposed to discharge refuse into either of said 15 receptacles, co-acting lugs on the annulus and chute for defining the two extreme positions of the chute, and a gate for closing the discharge end of said chute and yieldably urged to closed position.
- 20 6. A refuse disposal apparatus as embodied in claim 5 wherein the collar is provided with a recess, and an annulus with a lug extending into the recess for positioning the annulus in the collar.
- 25 7. An apparatus as embodied in claim 5 wherein the upper end of the chute is provided interiorly with a lip to facilitate rotation and removal of the chute.
